UNITED STATES PATENT OFFICE.

ISAAC LEIBOWITZ, OF WEST HOBOKEN, NEW JERSEY.

COMBINED CALENDAR AND BULLETIN.

Application filed February 27, 1923. Serial No. 621,503.

To all whom it may concern:

Be it known that I, ISAAC LEIBOWITZ, a citizen of the United States, residing at West Hoboken, in the county of Hudson and 5 State of New Jersey, have invented certain new and useful Improvements in Combined Calendars and Bulletins; and I do hereby declare the following to be a full, clear, and exact description of the invention, such as 10 will enable others skilled in the art to which it appertains to make and use the same, reference being had to the accompanying drawings, and to characters of reference marked thereon, which form a part of this specification. 15

This invention relates, generally, to improvements in calendars; and the invention has reference, more particularly, to a novel construction of combined calendar and information bulletin. 20

The invention has for its principal object to provide a novel construction and arrangement of calendar back and pad for use by societies, clubs, associations or other organizations desiring to disseminate information relative to its activities. To this end the novel calendar and bulletin is adapted to provide spaces in connection with the calendar leaves for special notices and bulletins 25 of events to occur during each month of the year, and a space on the calendar back for the setting forth of society or association rules, regulations and general information relative to the organization issuing the calendar, together with an indicating tab or 30 space in connection with each calendar leaf which will refer the user to the location of said rules, regulations and general information. Said calendar leaves being arranged in a novel lapped relation one to the other so that the said indicating spaces of 35 all leaves are constantly visible, thus reiterating and emphasizing the warning to the user as to the location of the said rules, regulations and general information which it is 40 desired to impress upon the user, whereby the psychological effect of arousing the user's curiosity and attention is made use of in bringing the user to uncover and read the 45 normally hidden information. 50

Other objects of this invention, not at this time more particularly enumerated, will be clearly understood from the following detailed description of the same.

The invention is clearly illustrated in the 55 accompanying drawings, in which:—

Figure 1 is a front elevation or face view of the novel combined calendar and information bulletin, made according to and embodying the principles of this invention; 60 Figure 2 is a side edge elevation of the same. Figure 3 is a fragmentary face view of the calendar pad alone; Figures 4, 5, 6 and 7 are similar views showing various leaves removed; Figure 8 is a fragmentary perspective view of the calendar pad. Figure 9 is a face view of the calendar back with the 65 pad removed.

Similar characters of reference are employed in all of the hereinabove described 70 views, to indicate corresponding parts.

Referring now to said drawings, the reference character 10 indicates the calendar back, which is preferably made of heavy card-board or any other suitable material. 75 The face of said calendar-back is divided in a suitable manner to provide a top panel or space 11 in which may be inscribed, in any suitable manner or in any desired arrangement presenting a decorative form, the name 80 of the organization issuing or distributing the calendar; a longitudinally central panel or space 12 providing the last page beneath the calendar pad which is designed to have inscribed or suitably displayed and set forth 85 therein the rules, regulations and general information relative to the organization issuing or distributing the calendar; and flanking each side of said central panel or space 90 12 are a series of longitudinally aligned panels or spaces 13 in which any desired advertising matter may be displayed. Said calendar back is also provided at or adjacent to its upper end with a central perforation 14, 95 engageable with a supporting means for hanging up the calendar.

Suitably secured to said calendar back 10, so as to be registered or aligned with the central panel or space 12 and to extend over the major part of the same except for an exposed 100 marginal portion adjacent to its lower end, is a calendar pad 15. Said calendar pad 15 is secured to the back 10 by staples or wire-stitching 16 passed through the upper end portion of the former, or by any other fastening means found convenient. Said calendar pad comprises twelve leaves 17, one for each month, all preferably attached to 105

the pad body 15 by perforated connection means 18, whereby each leaf may be readily torn away from the pad body when it is desired so to do. Each successive calendar leaf 5 is longer than the leaf overlying the same, whereby the lower end or bottom marginal portion 17^a of said underlying leaves is constantly visible. The thus constantly visible or exposed portions 17^a of the leaves provide a 10 notice space in which may be inscribed a notice or legend referring the user's attention to the last page or underlying space formed by the panel or space 12 wherein the rules, regulations and general information 15 are displayed concerning which it is desired to inform the user and by arousing curiosity induce the user to uncover. To further carry out the latter purpose, said panel or space 12 is longer than the last leaf of the calendar 20 pad so that an exposed or constantly visible lower marginal space 12^a is provided to contain a notice or legend advising the user that said panel or space 12 is the last page referred to by the notices or legends of the 25 calendar leaves 17. Each calendar leaf has inscribed thereon the monthly calendar 19, and also a space 20 in which notice may be given of the regular meetings of the organization issuing or distributing the calendar. 30 Since by reason of the successively greater length of the underlying leaves of the calendar, each of said underlying leaves possesses additional space 21 upon which may be inscribed or set forth more detailed 35 notices of special events of the year anticipated by the organization issuing or distributing the calendar, or said space may be devoted to any other matter it is the desire of the organization to keep before the attention 40 of its members or users of the calendar.

From the above description of the novel calendar arrangement it will be apparent that the same provides a novel structural arrangement and combination of parts peculiarly adapted to serve the purposes already above referred to, and adapted to arouse the user's curiosity and thus inspire investigation of the matter it is desired to keep before their attention.

50 I am aware that some changes or variations in the above described calendar structure may be made without departing from the scope of this invention; hence, I do not limit myself to the exact arrangements and 55 combinations of the several devices and parts

as described in the foregoing specification, nor do I limit myself to the exact details of the construction of the same as illustrated in the accompanying drawings.

I claim:—

1. A combined calendar and bulletin, comprising a calendar back having a bulletin space devoted to the display of information, a calendar pad attached to said back so as to normally cover and conceal the information displayed in the bulletin space of said calendar back, the successive leaves of said calendar pad being of progressively increased length to constantly expose the lower marginal portion of each leaf, said exposed 60 lower marginal portion of each leaf having displayed thereon a notice referring the user's attention to the concealed bulletin space of said calendar back, and said calendar pad being of less length than said bulletin space to provide a constantly exposed portion at the bottom of the latter having displayed thereon a notice identifying the bulletin space.

2. A combined calendar and bulletin, comprising a calendar back having its face divided into spaces to provide a name space at the upper end of said back, a central longitudinal bulletin space, and longitudinally aligned advertising spaces flanking each side 80 of said bulletin space; a calendar pad attached to said back so as to normally cover and conceal the information displayed in the bulletin space of said calendar back, the successive leaves of said calendar pad being of 85 progressively increased length to constantly expose the lower marginal portion of each leaf, said exposed lower marginal portion of each leaf having displayed thereon a notice referring the user's attention to the concealed bulletin space of said calendar back where 90 by said notice is reiterated and strongly impressed upon the reader's attention, and said calendar pad being of less length than said bulletin to provide a constantly exposed portion at the bottom of the latter having displayed thereon a notice identifying the 95 bulletin space.

In testimony, that I claim the invention set forth above I have hereunto set my hand 100 this 21st day of February, 1923.

ISAAC LEIBOWITZ.
